UNITED STATES PATENT OFFICE

JAN P. CLARY, OF HARTFORD, CONNECTICUT

DESIGN FOR AN AUTOMATIC INKWELL

Application filed May 6, 1931. Serial No. 39,733. Term of patent 14 years.

To all whom it may concern:

Be it known that I, JAN P. CLARY, a citizen of the United States of America, residing at Hartford, in the county of Hartford and State of Connecticut, have invented a new, original, and ornamental Design for an Automatic Inkwell, of which the following is a specification, reference being had to the accompanying drawings, forming part thereof.

Figure 1 is a front elevational view of the automatic inkwell, showing my new design;

Figure 2 is an end elevational view of the same.

I claim:

The ornamental design for an automatic inkwell, as shown.

JAN P. CLARY.
